INTEGRAL COVER AND HANDLE FOR A
PRINTED CIRCUIT BOARD MODULEWilliam Venema, North Haledon, N.J., assignor to
Vemaline Products Company, Inc., Franklin Lakes,
N.J., a corporation of New Jersey

Filed May 15, 1967, Ser. No. 7,121

Term of patent 14 years

(Cl. D26—5)

FIGURE 1 is a perspective view of the integral cover and handle for a printed circuit board module of the present invention, showing the module partially in dotted lines for illustrative purposes only.

FIGURE 2 is a front plan view of the integral cover and handle for a printed circuit board module of FIGURE 1.

FIGURE 3 is a right side view thereof.

FIGURE 4 is a back plan view thereof.

FIGURE 5 is a top plan view thereof.

A left side view thereof would be a mirror image of the right side view thereof.

A bottom plan view thereof would be a mirror image of the top plan view thereof of FIGURE 5.

I claim:

The ornamental design for an integral cover and handle for a printed circuit board module, substantially as shown and described.
